UNITED STATES PATENT OFFICE.

SAMUEL WERNER, OF BROOKLYN, NEW YORK.

SWEAT-BAND FOR HATS.

1,292,186.

Specification of Letters Patent. Patented Jan. 21, 1919.

Application filed March 8, 1916. Serial No. 82,784.

To all whom it may concern:

Be it known that I, SAMUEL WERNER, a citizen of the United States, and resident of Brooklyn, in the county of Kings and State of New York, have invented certain new and useful Improvements in Sweat-Bands for Hats, of which the following is a specification.

This invention relates to sweat bands for the inside of hats and consists of a band made of several pieces of sweat resisting material arranged end to end to make substantially a continuous band, the object of the invention being to aid in the adjustment 10 of the band, better ventilation about the band and cheapness of construction, as will be more fully explained and the details described in the following specification, set forth in the appended claims and illustrated in the accompanying drawings, wherein:

Figure 1, is a perspective view of a cap looking into the same and showing the improved sweat band.

25 Fig. 2, is a vertical sectional view of the cap looking toward the rear.

Fig. 3, is an elevation of the front section of the band.

30 Fig. 4, is a similar view of one of the side rear sections.

A sweat band of one piece as heretofore used often becomes uncomfortable because it tends to wedge the hat on the head of the wearer on account of the even surface 35 around the head and consequently confining the heated air within the hat.

The present invention provides a sweat band made of several pieces, the part 5 being adapted to fit the forehead of the wearer 40 and is located within the front of the cap. It is highest at the center and slopes toward the ends, its lower edge being stitched to the front edge of the cap.

Along the inner sides and at the rear of 45 the cap are also stitched the two sections 6, one of them being shown in Fig. 4 and the two may be joined at the rear of the cap by the knot 7 of ribbon or cord. These two sections are high at one end 8 and taper to 50 almost a point at the other end 9.

It is obvious that the shapes shown and described are not absolutely essential as it will be seen that this band permits the cap to be stretched about the head without the resistance of both band and cap.

The joints of the band at the ends of the sections permit of the access of air to the interior of the hat and perforations such as commonly used in sweat bands may be provided as shown.

As a source of economy small pieces of leather may be used to make up these bands and scraps can be cut to appropriate shapes to provide the sections above described. This construction is especially desirable 65 where sweat bands are needed for cheap grades of caps. These sections may also be let down below the cap for protecting the head, face and ears particularly in cold weather, a feature almost impossible with 70 the single piece sweat band.

What I claim as new is:

1. In a sweat band, the combination with a hat, of an interior band of several pieces abutting each other at the rear of the hat 75 and overlapping each other at the sides of the hat.

2. In a sweat band, the combination with a hat, of a front flexible band section terminating at the sides, and side sections overlapping the ends of the front section and abutting each other at the rear of the hat, the whole being stitched to the edge of the hat so that they may be separately folded downward and outward.

3. A sweat band for hats or caps comprising segmental sections engaging at the sides and rear portions of the hat or cap.

4. A sweat band for hats or caps comprising segmental sections adapted to be secured 90 within the hat or cap and having portions overlapping at the sides.

Signed at Brooklyn, in the county of Kings and State of New York, this 17 day of February, A. D. 1916.

SAMUEL WERNER.
